US0D1044212S

(12) United States Design Patent (10) Patent No.: US D1,044,212 S
(45) Date of Patent:  Oct. 1, 2024

(54) REVERSIBLE HAT

(71) Applicant: ZETAJAY S.R.L., Turin (IT)

(72) Inventor: Giacomo Macrì, Turin (IT)

() Term: 15 Years

(21) Appl. No.: 35/516,809

(22) Filed: Apr. 6, 2022

(80) Hague Agreement Data

Int. Filing Date: Apr. 6, 2022

Int. Reg. No.: DM/220402

Int. Reg. Date: Apr. 6, 2022

Int. Reg. Pub. Date: Apr. 7, 2023

(30) Foreign Application Priority Data

Oct. 7, 2021 (EM) 008719975-0005

(51) LOC (14) Cl. 02-03

(52) U.S. Cl.

USPC D2/879
